(57) **CLAIM**

The ornamental design for a BNC type connector, as shown and described.

DESCRIPTION

FIG. 1 is a front perspective view of a first embodiment of a BNC type connector showing my new design;

FIG. 2 is a top view thereof;

FIG. 3 is a bottom view thereof;

FIG. 4 is a front view thereof, enlarged for clarity of detail;

FIG. 5 is a back view thereof, enlarged for clarity of detail;

FIG. 6 is a front perspective view of a second embodiment of a BNC type connector showing my new design;

FIG. 7 is a top view thereof;

FIG. 8 is a bottom view thereof;

FIG. 9 is a front view thereof, enlarged for clarity of detail; and,

FIG. 10 is a back view thereof, enlarged for clarity of detail.

The broken lines in the figures show unclaimed detail only and form no part of the claimed design.
